[57] **CLAIM**

The ornamental design for a macaroni, as shown.

DESCRIPTION

FIG. 1 is a top plan view of a macaroni showing my new design.

FIG. 2 is a side elevational view.

FIG. 3 is a front elevational view.

FIG. 4 is an elevational view showing the side opposite that seen in FIG. 2.

FIG. 5 is a bottom plan view.

FIG. 6 is a rear elevational view; and

FIG. 7 is a front perspective view thereof.
